UNITED STATES PATENT OFFICE.

FREDERIC L. DEWEY, OF CANTON, ILLINOIS, ASSIGNOR TO PARLIN & ORENDSREF COMPANY, OF CANTON, ILLINOIS, A CORPORATION OF ILLINOIS.

CULTIVATOR.

1,161,114.

Specification of Letters Patent. Patented Nov. 23, 1915.

Application filed May 12, 1915. Serial No. 27,556.

To all whom it may concern:

Be it known that I, FREDERIC L. DEWEY, a citizen of the United States, and a resident of Canton, in the county of Fulton, 5 State of Illinois, have invented certain new and useful Improvements in Cultivators, of which the following is a specification, reference being had to the accompanying drawings.

10 My invention relates to cultivators and it has for its principal object the provision of new and improved means for regulating the depth at which the ground stirring appliance shall work.

15 It is one of the objects of my invention to provide suitable regulating means controlling the position of the gangs without the use of hand levers standing up in the way of the driver and interfering with his 20 handling of the team and the plow.

25 It is another object of my invention to provide a construction and arrangement of spring devices which shall serve to assist in the raising of the gangs and also to cushion 30 the gangs so as to cause them to work normally at a predetermined depth, but so arranged that the gangs are capable of being moved downward by the operator to follow inequalities of the ground or to effect deeper 35 plowing as desired.

40 It is another object of my invention to provide in connection with this improved spring construction means for shifting the supporting wheels backward when the gangs 45 are raised out of operative ground-engaging position so as to maintain the proper balance of the machine as a whole.

The preferred means by which I have 50 accomplished my several objects are illustrated in the accompanying drawings and are hereinafter specifically described.

That which I believe to be new and desire to cover by this application is set forth in the claims.

45 In the drawings:—Figure 1 is a side elevation of my improved machine, with one of the supporting wheels removed; Fig. 2 is a similar view but showing the position which the parts assume when the gangs are 50 held in raised position; Fig. 3 is a top view of the parts as shown in Fig. 1, but with both supporting wheels in position upon the plow; Fig. 4 is a fragmentary view, being an enlarged detail showing the construction

and arrangement of the parts by which the 55 lower end of the springs utilized for controlling the position of the gangs is connected with the gangs; Fig. 5 is a side view of one of the arm members shown in Fig. 4; and Fig. 6 is a fragmentary view, being 60 an enlarged detail showing the part to which the upper end of the spring is connected, being shown substantially as seen at the line 6—6 of Fig. 1.

Referring to the several figures of the 65 drawings in which corresponding parts are indicated by the same reference characters,—15 indicates a laterally-extending sleeve having mounted in its ends the upper horizontal portions of axle members 16—70 17, upon the lower horizontal portions of which are journaled supporting wheels 18—19, respectively. Hounds 20—21 are connected in any suitable manner at their forward ends to a tongue 22 and at their 75 rear ends are connected by means of brackets 23—24 to the transversely-extending sleeve 15. The upper horizontal portion of an arch 25 is connected in any suitable manner to the rear end of the tongue, the hounds 80 20—21 being connected to the vertically-extending portions of the said arch 25 by means of suitable clips 26—27. Upon the lower horizontally-extending portions of the arch member 25 are revolvably mounted 85 sleeves 28—29 to which the plow beams are adjustably connected. Each gang comprises beams 30 carrying ground-working appliances 31 and provided with a handle 32 and a stirrup 33 for the convenience of the operator. The gangs are connected to the sleeves 28 by means of yokes 34 which are, by means of vertically extending pins or bolts 35, pivotally connected with sleeves 36 which are feathered upon the sleeves 28—29 90 95 and are adapted to be held by means of set-screws in any desired adjusted position along such sleeves. The framework is further supported by means of diagonally-extending seat supporting bars 38—39 which 100 are connected at their forward ends to the hounds 20—21 and to the sleeves 15, being provided at their rear ends with a seat 40 of any suitable type.

Clamped upon the outer end of each of the 105 sleeves 28—29 is an arm 41 by which the draft devices are connected to the arch 25 and by which the said arch 25 is connected

to the wheel arch comprising the sleeve 15 and the axle members 16—17. The connection between the said two arches is effected by means of adjustable diagonally-disposed links 42 which are pivotally connected at their lower ends to the lower ends of the arms 41, and which are pivotally connected at their rearward upper ends to clips 43 fixed upon the vertically-extending portions 5 of the axle members 16—17. Each of the clips 43 is also provided with an inwardly-extending hook member 44 over which the outer one of the beams 30 is adapted to be slipped for holding the gangs in raised position, as shown in Fig. 2. Draft bars 45 are pivotally connected at their upper ends to a transversely-extending evener 46 which is pivotally mounted by means of a bolt 47 upon the tongue 22. The lower ends of the bars 45 are connected by means of flexible connectors 48 of any suitable type with the lower ends of the arms 41.

The gang arch 25 is braced and held against turning relative to the framework 25 of the machine by means of diagonally-extending bars 49 which have their lower ends pivotally mounted upon the horizontally-extending portions of the said arch 25 adjacent to the outer ends of the sleeves 28—29, said bars 49 being connected at their upper ends by means of bolts 50 with the brackets 23—24, respectively. As is best shown in Fig. 6, the bolts 50 also pivotally support rock-arms 51, short brace-bars 52 being provided for bracing the bolts 50 relative to the bars 49. The lower end of the rock-arm 51 at each side of the machine is connected by means of a coiled expansion spring 53 with the arm 41 at that side of the machine, the connection between the spring and the arm 41 being effected by means of a link 54. The rock-arm 51 is provided with a lug 55 extending from its forward face adapted to engage the brace-bar 52, as is best shown in Fig. 6, to limit the turning of the arm 51 in counterclockwise direction in Figs. 1 and 2. Each of the springs 53 is thus adapted to exert a backward pull upon the arm 41 with which it is connected.

50 Revolubly mounted upon the outer end of the horizontally-extending portion of the arch 25 at each side of the machine is an arm 56 which is provided with a laterally-extending lug 57 which is adapted to engage a 55 rearwardly-extending lug 58 carried by the plate 41 at that side of the machine. The lower end of the arm 56 at each side of the machine has pivotally connected to it the lower end of the diagonally-extending rod or link 59, the upper end of which rod or link passes through a suitable opening in the upper end of the rock-arm 51, having a hand wheel 60 secured by means of screw-threads upon its upper end. Thus through 60 the use of the hand wheel 60 upon the rods

59 the vertical position of the arms 56 can be easily and readily controlled by the operator in position in his seat.

With the gangs in raised position, as shown in Fig. 2, the lugs 55 carried by the rock-arms 51 will be in contact with the brace-bars 52. The lugs 58 carried by the arms 41 will have been turned upward out of contact with the lugs 57 carried by the arms 56. Upon the lowering of the gangs, and the forward movement of the arms 41, the springs 53 will be stressed, but not sufficiently to prevent the normal downward movement of the gangs. When the stop-lugs 58 are brought into contact with the lugs 57 80 of the arms 56, however, the normal downward movement of the gangs will be stopped. If it is desired that the gangs be moved still farther downward, this can be accomplished by the application of a proper pressure upon the gangs by the operator. Upon such further downward movement of the gangs after the stop-lugs 58 have come in contact with the lugs 57, the arms 56 will be swung downward, causing the rock-arms 51 to be swung 90 in clock-wise direction in Figs. 1 and 2. Thus upon a movement of the gangs downward after the lugs 58 have come in contact with the lugs 57, the lower ends of the springs 53 are moved downward and at the 95 same time the upper ends of the said springs are moved upward, the effect of the springs 53 to resist the downward movement of the gangs being thus twice as great after the engagement of the lugs 58 and 57 as that before 100 such engagement of the said lugs. The effective strength of the spring 53 and the proportions of the several parts are designed to be such that the gangs will normally work at substantially the depth at which the lugs 58 105 and 57 are first brought into contact in the downward movement of the gangs, in which position the lugs 55 are still in engagement with the brace-bars 52. With the parts constructed and arranged in this manner, it 110 will be readily understood that the position at which the gangs normally work can be easily and quickly regulated by a proper adjustment of the hand wheels 60 upon the rods 59, by which adjustment the normal position of the lugs 57 is regulated.

As will be readily appreciated from an inspection of Figs. 1 and 2, when the gangs are raised the supporting wheels are moved backward relative to the frame through the 115 medium of the bars 42. The tendency of the wheels to lag behind in the forward movement of the machine is thus utilized to assist in the raising of the gangs. Inasmuch as the shifting of the wheels backward also 120 lowers the frame slightly, it will be seen that the weight of the frame and of the driver also assist slightly in the gang-raising operation. The backward movement of the 125 wheels compensates for the added weight of 130

the gangs brought to bear upon the frame in rear of the axle.

What I claim as my invention and desire to secure by Letters Patent, is—

5 1. In a cultivator, the combination of a frame, ground working appliances swingingly mounted relative to said frame, an arm adapted to swing with said ground working appliances, a second arm pivotally mounted relative to said first-named arm and adapted to be engaged thereby, a rock-arm pivotally mounted on said frame, and yielding means tending to hold said first-named arm in raised position relative to 10 said rock-arm.

2. In a cultivator, the combination of a frame, ground working appliances swingingly mounted relative to said frame, an arm adapted to swing with said ground 20 working appliances, a second arm pivotally mounted relative to said first-named arm and adapted to be engaged thereby, means for adjusting the position at which said second arm shall stand and at which it shall be 25 engaged by said first-named arm, a spring adapted to resist the downward swinging of said ground working appliances, and means actuated by the movement of the second arm with said first-named arm for additionally 30 stressing said spring as said ground working appliances move downward after the engagement of said two arms.

3. In a cultivator, the combination of a frame, ground working appliances swingingly mounted relative to said frame, an arm adapted to swing with said ground working appliances, a second arm pivotally mounted relative to said first-named arm and adapted to be engaged thereby, means for adjusting the position at which said second arm shall stand and at which it shall be 35 engaged by said first-named arm, a coiled expansion spring adapted to have its lower end moved downward by the downward 40 movement of the ground working appliances, and means actuated by the movement of said second arm with said first-named arm for moving the upper end of said spring upward as said ground working appliances 45 move downward after the engagement of said two arms.

4. In a cultivator, the combination of a frame, ground working appliances swingingly mounted relative to said frame, an arm adapted to swing with said ground working appliances, a second arm pivotally mounted relative to said first-named arm and adapted to be engaged thereby, a rock-arm pivotally mounted on said frame, a spring connected at its upper end to one 55 end of said rock-arm and at its other end to said first-named arm, and connections between the other end of said rock-arm and said second-named arm.

5. In a cultivator, the combination of a

frame, ground working appliances swingingly mounted relative to said frame, an arm adapted to swing with said ground working appliances, a second arm pivotally mounted relative to said first-named arm and adapted to be engaged thereby, a rock-arm pivotally mounted on said frame, a spring connected at its upper end to one end of said rock-arm and at its other end to said first-named arm, a stop adapted to limit the turning of the rock-arm under the influence of the said spring, and connections between the other end of said rock-arm and said second-named arm.

6. In a cultivator, the combination of a frame, ground working appliances swingingly mounted relative to said frame, an arm adapted to swing with said ground working appliances, a second arm pivotally mounted relative to said first-named arm and adapted to be engaged thereby, a rock-arm pivotally mounted on said frame, a spring connected at its upper end to one end of said rock-arm and at its other end to said first-named arm, and adjustable connections 85 between the other end of said rock-arm and said second-named arm.

7. In a cultivator, the combination of a frame, ground working appliances swingingly mounted relative to said frame, an arm adapted to swing with said ground working appliances, a second arm pivotally mounted relative to said first-named arm and adapted to be engaged thereby, a rock-arm pivotally mounted on said frame, a spring connected 90 at its upper end to one end of said rock-arm and at its other end to said first-named arm, a stop adapted to limit the turning of the rock-arm under the influence of the said spring, and adjustable connections between 95 the other end of said rock-arm and said second-named arm.

8. In a cultivator, the combination of a frame, ground working appliances movable up and down relative to said frame, a rock-arm pivotally mounted relative to said frame, yielding means bearing on said rock-arm adapted to be stressed by the downward movement of the ground working appliances independently of the turning of said rock-arm, and connections between said rock-arm and said ground working appliances effective at a predetermined point in the downward movement of the ground working appliances for swinging said rock-arm for additionally stressing said yielding means.

9. In a cultivator, the combination of a frame, ground working appliances movable up and down relative to said frame, a rock-arm pivotally mounted relative to said frame, yielding means bearing on said rock-arm adapted to be stressed by the downward movement of the ground working appliances independently of the turning of said rock-arm, and adjustable connections between 110 115 120 125 130

said rock-arm and said ground working appliances effective at the desired point in the downward movement of the ground working appliances for swinging said rock-arm for additionally stressing said yielding means.

10. In a cultivator, the combination of a frame, ground working appliances movable up and down relative to said frame, a rock-arm pivotally mounted relative to said frame, yielding means bearing on said rock-arm adapted to be stressed by the downward movement of the ground working appliances independently of the turning of said rock-arm, a rod passing through the said rock-arm, means on the upper end of said rod within convenient reach of the operator for adjusting the position of the rod relative to said rock-arm, and means actuated by the downward movement of the ground working appliances for moving said rod downward for additionally stressing said yielding means after the ground working appliances have reached their normal working position.

11. In a cultivator, the combination of a frame, ground working appliances movable up and down relative to said frame, a rock-arm pivotally mounted relative to said frame, yielding means bearing on said rock-arm adapted to be stressed by the downward movement of the ground working appliances independently of the turning of said rock-arm, a rod passing through the said rock-arm, means on the upper end of said rod within convenient reach of the operator for adjusting the position of the rod relative to said rock-arm, a stop device operatively connected with said rod, and a co-operating stop device moved downward by the downward movement of the ground working appliances adapted to be brought into engagement with said first-named stop device at some point in the downward movement of the ground working appliances depending upon the adjustment of the said rod, the further downward movement of the ground working appliances after the engagement of said two co-operating stop devices being adapted to swing said rock-arm for additionally stressing said yielding means.

12. In a cultivator, the combination of a frame, ground working appliances movable up and down relative to said frame, an arm pivotally mounted relative to said frame, connections between said arm and said ground working appliances whereby said arm is swung relative to the frame as the ground working appliances are moved up and down, a second arm pivotally mounted relative to said first-named arm and adapted to be engaged thereby, a rock-arm pivotally mounted on said frame, and yielding means having bearings on one end of said rock-arm and on said first-named arm tending to hold said parts yieldingly against movement away from each other.

13. In a cultivator, the combination of a frame, ground working appliances movable up and down relative to said frame, an arm pivotally mounted relative to said frame, connections between said arm and said ground working appliances whereby said arm is swung relative to the frame as the ground working appliances are moved up and down, a second arm pivotally mounted relative to said first-named arm and adapted to be engaged thereby, a rock-arm pivotally mounted on said frame, yielding means having bearings on one end of said rock-arm and on said first-named arm tending to hold said parts yieldingly against movement away from each other, and connections between the other end of said rock-arm and said second-named arm.

14. In a cultivator, the combination of a frame, ground working appliances movable up and down relative to said frame, an arm pivotally mounted relative to said frame, connections between said arm and said ground working appliances whereby said arm is swung relative to the frame as the ground working appliances are moved up and down, a second arm pivotally mounted relative to said first-named arm, lugs carried by said arms adapted to be brought into engagement with each other in the swinging of said arms, yielding means tending to prevent the swinging of the first-named arm upon the downward movement of the ground working appliances, and means actuated by the movement of said second arm after the said lugs are brought into engagement with each other for additionally stressing said yielding means upon the further downward movement of the ground working appliances.

15. In a cultivator, the combination of a frame, ground working appliances movable up and down relative to said frame, an arm pivotally mounted relative to said frame, connections between said arm and said ground working appliances whereby said arm is swung relative to the frame as the ground working appliances are moved up and down, a second arm pivotally mounted relative to said first-named arm, lugs carried by said arms adapted to be brought into engagement with each other in the swinging of said arms, yielding means tending to prevent the swinging of the first-named arm upon the downward movement of the ground working appliances, means actuated by the movement of said second arm after the said lugs are brought into engagement with each other for additionally stressing said yielding means upon the further downward movement of the ground working appliances, and adjustable means for regulating the position at which said lugs shall be brought into operative engagement with each other.

16. In a cultivator, the combination of a frame, ground working appliances movable up and down relative to said frame, an arm pivotally mounted relative to said frame, 5 connections between said arm and said ground working appliances whereby said arm is swung relative to the frame as the ground working appliances are moved up and down, a second arm pivotally mounted 10 relative to said first-named arm, lugs carried by said arms adapted to be brought into engagement with each other in the swinging of said arms, yielding means having bearings one of which is adapted to be 15 moved for stressing the said yielding means upon the downward movement of the ground working appliances, and means actuated by the movement of said second arm after the 20 said lugs are brought into engagement with each other for moving the other of said bearings for additionally stressing said yielding means.

17. In a cultivator, the combination of a frame, ground working appliances movable 25 up and down relative to said frame, an arm pivotally mounted relative to said frame, connections between said arm and said ground working appliances whereby said arm is swung relative to the frame as the 30 ground working appliances are moved up and down, a second arm pivotally mounted relative to said first-named arm, lugs carried by said arms adapted to be brought into engagement with each other in the swinging 35 of said arms, yielding means having bearings one of which is adapted to be moved for stressing the said yielding means upon

the downward movement of the ground working appliances, means actuated by the movement of said second arm after the said 40 lugs are brought into engagement with each other for moving the other of said bearings for additionally stressing said yielding means, and adjustable means for regulating the position at which said lugs shall be 45 brought into operative engagement with each other.

18. In a cultivator, the combination of a frame, ground working appliances movable up and down relative to said frame, an arm pivotally mounted relative to said frame, 50 connections between said arm and said ground working appliances whereby said arm is swung relative to the frame as the ground working appliances are moved up and down, a second arm pivotally mounted 55 on the axis of said first-named arm, a lug carried by said first-named arm extending over said second-named arm and adapted to engage the same upon the downward 60 movement of said first-named arm, yielding means having bearings one of which is adapted to be moved for stressing said yielding means upon the downward movement of the ground working appliances, adjustable means for regulating the position 65 at which said second arm shall stand normally, and means actuated by the movement of said second arm when moved downward by said first-named arm for moving 70 the other of the bearings of said yielding means for additionally stressing said yielding means.

FREDERIC L. DEWEY.
